Primary Examiner — Jennifer L Rempfer*Assistant Examiner* — Adrienne Corra(74) *Attorney, Agent, or Firm* — Rosenberg, Klein & Lee(57) **CLAIM**

The ornamental design for a mesh cap as shown and described.

DESCRIPTION

FIG. 1 is a perspective view of a mesh cap showing my present design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view thereof.

The thick broken lines shown along the panels are sewing threads of the mesh cap. The thin broken lines shown on the bill illustrate portions of the mesh cap which form no part of the claimed design.
